UNITED STATES PATENT OFFICE.

WALTER S. MINOR, OF CUNNINGHAM, TENNESSEE.

STAVE-JOINTING MACHINE.

1,229,307.

Specification of Letters Patent. Patented June 12, 1917.

Application filed October 23, 1916. Serial No. 127,232.

To all whom it may concern:

Be it known that I, WALTER S. MINOR, a citizen of the United States, residing at Cunningham, in the county of Montgomery and State of Tennessee, have invented certain new and useful Improvements in Stave-Jointing Machines, of which the following is a specification, reference being had to the accompanying drawings.

10 This invention relates to an improved stave jointing machine and has for its primary object to provide a machine whereby the staves of barrels or hogsheads may be quickly and accurately cut at the proper 15 angle for jointing, irrespective of the width of the stave.

It is another object of the invention to provide a machine for the above purpose embodying a traveling carriage and means 20 for automatically removing the jointed stave at the end of the operative movement of the carriage.

The invention has for another important 25 object to provide operating means for the traveling carriage, and means automatically actuated by the carriage to render said operating means operative and inoperative and to reverse the movement of the carriage after the discharge of the jointed stave.

30 It is also an important object of my invention to provide improved means for discharging the cut strips from the machine in the reverse or return movement of the carriage.

35 In its more specific aspect, the present invention embodies a divided carriage, one section of the carriage being mounted on a relatively stationary frame and the other upon a transversely tilting frame, a rotary 40 saw mounted upon each of the frames, and means for adjusting the tiltable frame so as to space the rotary saws in accordance with the width of the stave, whereby the edges of the stave are cut on the proper angle.

45 It is also one of the detail items of improvement to provide a sectional traveling carriage and means for holding the stave in position upon said carriage.

The invention has for a further general 50 object to improve and simplify the construction of machines of the above character and render the same highly reliable and efficient in practical operation, not liable to get out of order, and capable of manufacture 55 at relatively small cost.

With the above and other objects in view, my invention consists in the novel features of construction, combination and arrangement of parts to be hereinafter more fully described, claimed and illustrated in the accompanying drawings, in which,

Figure 1 is a top plan view of a stave jointing machine constructed in accordance with the preferred embodiment of the invention:

Fig. 2 is a transverse section taken on the line 2—2 of Fig. 1;

Fig. 3 is a longitudinal section taken on the line 3—3 of Fig. 2, the discharge end of the machine being omitted;

Fig. 4 is a fragmentary side elevation illustrating the means for actuating the vertically swinging strip boards;

Fig. 5 is an enlarged vertical section through the discharge end of the machine;

Fig. 6 is a transverse section taken on the line 6—6 of Fig. 5;

Fig. 7 is a plan view showing the automatic clutch shifting means in one position of the traveling carriage with the clutch in neutral position;

Fig. 8 is a similar view, the clutch being in operative engagement with one of the power transmission pulleys, and showing the carriage near the end of its operating movement;

Fig. 9 is a detail vertical sectional view showing the stave holding dogs at the forward end of the carriage; and

Fig. 10 is a similar view showing the holding dogs at the rear end of the carriage.

Referring in detail to the drawings, 5 designates the stationary frame section of the machine which is mounted upon a suitable base 6. A relatively narrow, vertically tilting frame section 7 is arranged at one side of the frame section 6, said frame sections being hingedly connected to each other at spaced points, as shown at 8. In the frame section 5, the transverse countershaft 9 is journaled in suitable bearings, and a similar countershaft 10 is also journaled in the tilting frame section 7 and connected to the countershaft 9 by a universal joint 11.

A saw mandrel 12 is mounted in suitable bearings 13 on the top of the main frame section 5 and a similar mandrel 14 is also mounted in bearings 15 on the top of the frame section 7. Circular saws 16 and 17 respectively, are fixed upon the opposed ends 110

of the mandrels 12 and 14. These saws are in radial alinement with the hinges 8 connecting the two sections of the frame, this point representing the axial center of a hogshead or barrel. The saw 16 on the stationary frame section 5 at all times remains in a vertical plane coinciding with this center, while the other saw 17 is always disposed at an angle to the perpendicular, 10 but in any of such angular positions on a radial line coinciding with the hinge or pivotal center of the tilttable frame section.

The stave to be cut or jointed is conveyed to the saws by means of a carriage. This carriage likewise consists of two sections 18 and 19 respectively, which are mounted for longitudinal traveling movement upon the frame sections 5 and 7. The carriage sections 18 and 19 are loosely coupled or connected to each other, as indicated at 20, so as to permit of the angular movement of the section 19 with respect to the section 18. Each of these carriage sections is provided with a pair of rollers 21 to travel upon a 25 track rail 22 suitably secured to each of the frame sections. To each carriage section, adjacent its upper edge, bracket members 23 are secured, and between the bracket members and the carriage a guide rail 24, suitably secured to the frame, is disposed, whereby the carriage is properly guided in its movement and held against transverse movement at its upper edge with respect to the frame section upon which it is mounted. 35 The carriage section 18 carries a longitudinally extending rack bar 25 having rack teeth on its lower edge to engage the teeth of a gear 26 fixed upon one end of a shaft 27 mounted in the main frame section 5.

40 Upon the frame section 5, a longitudinal rod 28 is mounted for sliding movement in the supporting brackets 29. This rod is in two sections, and between the same a coil spring 30 is interposed and suitably connected at its extremities to the rod sections. The extremities of the rod 28 are angularly and outwardly disposed, as at 31, for a purpose which will hereinafter appear.

A second longitudinally disposed rod 32 is also mounted upon the frame section 5 for rotative movement, and this rod is provided with spaced, radially projecting pins designated 33, 34, 35, 36, and 37 respectively. Upon the frame 5, adjacent to the respective pins 33, 34, 36 and 37 on the shaft 32, horizontally disposed, angular levers 38, 39, 40 and 41 respectively are arranged. These levers have their angularly disposed ends 38', 39', 40' and 41' respectively, disposed contiguous to the shaft 32, while the other arms of the levers are pivoted upon the frame 5 and project outwardly beyond the side thereof, as clearly shown in Figs. 7 and 8. The angular arms of the levers 38 and 39 60 project toward each other and are disposed

against the outer sides of the pins 33 and 34, whereas the angular arms of the levers 40 and 41 extend in relatively opposite directions and also engage against the other sides of the pins 36 and 37. The rod 32 extends forwardly to the front of the machine and has a suitable operating lever 42 connected to said end of the rod, whereby it may be manually actuated. A transverse bar 43 is slidably mounted upon the frame section 5 of the machine and carries a yoke 44 for engagement with the grooved collar 45 of a double clutch 46 which is keyed for sliding movement upon the shaft 27. Spaced belt wheels 47 are loosely mounted upon said shaft, with which the respective clutch heads engage. The sliding bar 43 has an opening 48 therein to receive the pin 35 on the shaft 32. A twisted power transmission belt 49 connects one of the wheels 47 with a belt 50 fixed upon the countershaft 9, and a similar wheel 51 is connected by the straight belt 52 to the other of the wheels 47. A lug 53 is fixed upon the section 18 of the traveling carriage to co-act with the outwardly projecting ends of the pivoted levers 38, 39, 40 and 41, whereby the clutch 46 is automatically shifted to operatively connect the wheels 47 to or disconnect the same from the shaft 27, in the manner which will be presently explained.

Upon each of the frame sections 5 and 7, a strip receiving board 54 and 55 respectively is pivotally mounted as at 56, for vertical swinging movement. Each of these boards carries an angularly disposed cleat 57 on its upper surface normally disposed in spaced relation to the respective saw blades. A fixed or stationary obliquely inclined deck 58 and 59 respectively is mounted upon each section of the frame. The strip boards 54 and 55 are each actuated through the medium of vertically movable rods indicated at 60, said rods being connected at their upper ends to the respective strip receiving boards. 100 A sectional shaft 61 is mounted in the frame sections 5 and 7, said shaft sections being connected by a universal joint 62 which, of course, is in alinement with the countershaft joint 11 and the hinges between the frame sections. To each section of the shaft 61, a downwardly projecting crank arm 63 is fixed, and to said arms the lower ends of the respective rods 60 are operatively connected. An upwardly projecting rod 64 is also fixed in one section of the shaft 61 and, to the same, one end of a link 65 is pivotally connected. The other end of this link is slotted, as at 66, to receive a pin 67 fixed in the lever 68 adjacent to its lower end. This lever, at its upper end, is pivoted as at 69 upon a lug or bracket 70 fixed to the frame section 7. To the section 19 of the traveling carriage, a projecting pin or lug 71 is secured to engage the lower end of the lever 68 and actuate the 110 120 125 130

several elements associated therewith in the return movement of the carriage after the stave has been cut, whereby the strip receiving boards 54 and 55 are elevated to the position seen in dotted lines in Fig. 2. The strips which have been cut from the edges of the stave are carried by the cleats 57 and directed over and upon the inclined decks 58 and 59 down which they move by gravity and are discharged upon the ground.

The stave to be jointed is securely held in position upon the carriage by means of the dogs 72 which are pivotally mounted as at 73 upon the forward ends of the carriage sections, the other ends of said dogs having lugs or shoulders 74 thereon which are held in engagement over the end of the stave resting upon the longitudinally curved upper edges of the carriage sections by means of the springs 75.

A dog 76 is also pivotally mounted as at 77 upon the rear end of each carriage section and has an angular lug 78 on its upper end for engagement over the end of the stave while at its lower end each dog is formed with an angularly and downwardly projecting arm 79. A coil spring 80 is connected to each of these dogs 76 above its pivot to normally hold the same in yielding engagement upon the stave. The arms 79 of the latter dogs are adapted for sliding engagement upon a fixed trip plate 81 mounted upon each frame section, and as seen in Fig. 5, the dogs are thereby rocked upon their pivots and the upper ends 78 thereof disengaged from the stave. At the rear end of the machine above the plate 81, spaced transverse rollers 82 are journaled at their ends in suitable bearings or supports, and a forwardly and downwardly inclined guide 83 is fixed to the support and has its lower end angularly bent and upwardly deflected, as at 83'. A rod 84 is suitably fixed upon each of the plates 81 and also has an upwardly and rearwardly projecting, angular portion disposed in parallel relation to the guide 83 and terminating at its upper end contiguous to the rollers 82. Rearwardly of these rollers 82, a third roller 85 is suitably mounted. The upper roller 82 is positively driven by a belt 86 which is engaged upon the wheel 87 fixed upon one end of the roller shaft, said belt passing around idler wheels 88 mounted upon the frame section 5 through a belt wheel 89 fixed on the countershaft 9. Thus, when the stave is released from the holding dogs 76, the rods 84 engaging against the under face of the stave as seen in Fig. 5, raise or elevate the same in the continued travel of the carriage and direct the stave between the rollers 82. The upper roller being positively driven, continues the movement of the stave rearwardly and over the roller 85, from which it is finally discharged.

When the carriage is at the forward end of the machine in position to receive a stave, it will be understood that the carriage section 18 engaging the angular forward end of the rod 28 has forced the rod forwardly 70 and expanded the spring 30, said spring acting to start the carriage upon its operative movement. In order to retain the carriage in this position, I have provided a suitable latch or holding mechanism which is illustrated more particularly in Fig. 3 of the drawings. This latch device consists of a rod 90 which is yieldingly held against movement by the spring 91 connected to one end of the rod, the other end of said rod 80 having an angularly disposed lug 92 formed thereon. 93 designates a guard plate suitably fixed upon the frame section 5, extending over the rack bar 25 and having its forward end angularly and downwardly 85 projected, as at 94. A lever 95 is fulcrumed intermediate of its ends upon the under side of this guard plate, as at 96, and one end of this lever is connected by the link 97 to the forward end of the latch rod 90. A vertically disposed rod 98 is pivotally connected to the other end of this lever and normally extends above the upper edge of the carriage section 18. Upon the upper edge of the rack bar 25, a shoulder 99 is formed, 95 with which the lug 92 on the latch rod 90 is adapted to coact, whereby the rack bar and consequently the carriage upon which the rack bar is secured, is held against longitudinal movement under the action of the 100 spring 30. It will be seen from this arrangement that, when the stave is placed in position upon the sectional carriage, it will engage the upper end of the rod 98 and force said rod downwardly, thus rocking 105 the lever 95 and lifting the forward end of the latch rod 90 so that the spring 30 may contract and start the carriage upon its operative movement.

A rock shaft 100 is mounted in suitable 110 bearings on the base 6 at the outer side of the tilting frame section 7. Spaced arms 101 are fixed upon this shaft and rods 102 pivotally connect the respective arms to the frame section 7 adjacent its upper end. An 115 operating lever 103 is fixed to one end of the shaft 100 and is provided with the usual spring pressed locking dog for engagement with the teeth of a fixed rack or quadrant 104. It will thus be seen that, by the manipulation of the lever 103, the frame section 7 may be tilted to any desired angle and the rotary saw blade 17 disposed in proper position relative to the opposed saw blade 16, in accordance with the width of the stave to 120 be cut.

Upon the countershaft 9, a belt wheel 105 is fixed, with which the driving belt 106 extending from any suitable source of power, is engaged. A large belt wheel 107 130

is fixed upon the countershaft section 9 and a similar wheel 108 upon the shaft section 10. These wheels are connected by the power transmission belts 109 and 110 respectively, to the relatively small belt wheels 111 and 112 upon the respective saw mandrels 12 and 14, so that the saws 16 and 17 will be driven at a very high speed.

A transverse shaft 113 is also mounted in 10 suitable bearings on the frame section 5 between and in parallel relation to the countershaft 9 and the shaft 27, and upon one end of this shaft 113 a suitable fan 114 is secured. This fan shaft is driven from a 15 belt wheel 115 fixed upon the countershaft 9 connected by a suitable driving belt 116 to a small belt wheel fixed upon the shaft 113. This fan is provided for the purpose of creating a current of air in proximity to the 20 dogs or levers 38 and 39 and preventing the collection of sawdust thereon which might possibly interfere with their proper operation.

Having now described the construction 25 and arrangement of the several parts of the machine, its operation will be understood as follows. After the frame section 7 has been properly adjusted to dispose the saw blade 30 at the desired angle with respect to the relatively stationary blade 16, the stave to be jointed is placed upon the upper edges of the two carriage sections 18 and 19, the forward end of the stave being forced downwardly under the dogs 76. The other end 35 of the stave is then pressed downwardly until it is in contact with the upper curved edges of the carriage sections, when the dogs 72 will snap over the stave ends and thus hold the same against movement on the carriage. As above stated, in this application of 40 the stave to the carriage, the latch element 90 is actuated to release the rack bar 25. The spring 30 will thus contract which, together with a forward push on the carriage by the 45 operator, will cause the lug 53 on the carriage section 18 to engage the first of the pivoted levers or dogs 38. The angular end of this lever engaging the pin 33, rocks the shaft 32 in the proper direction to cause the 50 pin 35 on said shaft to shift the sliding bar 43, thus shifting the double clutch 46 so as to operatively engage one of the clutch heads with one of the belt wheels 47 to which the belt 49 is connected. The shaft 27 is 55 thereby rotated and the gear 26 on this shaft co-acting with the teeth of the rack bar 25 continues the movement of the carriage, the two carriage sections moving together upon the respective frame sections 5 and 7. 60 The saws 16 and 17 respectively operate upon the opposite edges of the stave to cut or bevel the same upon the required angle. This rocking movement of the shaft 32 also causes the pin 36 to act upon the pivoted 65 lever 40 and dispose the same in a position at

right angles to the line of movement of the carriage. When the lug 53 on the carriage reaches this lever 40, it will engage said lever and rock the shaft 32 in a reverse direction, thereby returning the double clutch to 70 its neutral position. The momentum of the carriage is sufficiently great to carry the lug 53 beyond the pivoted lever 41, said lever returning to its normal position in the path of movement of the lug. The stave 75 is released from the carriage and discharged from the machine in the manner above referred to, and the carriage finally engages the angular end 31 of the rod 38 which acts as a bumper. The spring 30, by its contractile action, starts the carriage upon its return movement so that the lug 53 will engage the end of the lever 41 and rock the shaft 32 in a direction to shift the bar 43 so that the clutch 46 is operatively engaged 80 with the other of the belt wheels 47, thus reversing the rotation of the shaft 27 and consequently the movement of the carriage so that the return movement of the latter will be automatically continued. The lever 90 or dog 39 will have assumed a position at right angles to the line of movement of the carriage, and when the lug 53 engages this lever, the rocking movement of the shaft 32 will again return the double clutch to its 95 neutral position while the momentum of the carriage will be sufficient to return the same to its initial position where it is held by the latch rod 90. The guard plate 93 obviates liability of the legs or clothing of the operator coming in contact with the rack bar 100 25. It will thus be seen that the machine is practically automatic in its action after the carriage has been started upon its movement and the lug 53 engaged with the first 105 of the dogs or levers 38.

It will, of course, be understood that in the forward travel of the carriage, when the stave is being cut or jointed, the lug 71 on the carriage section 19 will engage the lower 110 end of the lever 68 and move past the same. The pin 67 on the lever moves in the slot 66 of the connecting bar 65 so that no movement will be transmitted to the vertical rods 60. Upon the return movement of the carriage, 115 however, the lug 71 engaging the lower end of the lever 68 causes a pull upon the bar 65, thereby rocking the jointed shaft 61 and forcing the rods 60 upwardly so as to elevate the strip receiving boards 54 and 55 and 120 discharge the strips therefrom upon the inclined decks 58 and 59, as heretofore explained. The strip boards immediately return to their normal horizontal positions by gravity after the lug 71 passes beyond the 125 end of the lever 68 in the return movement of the carriage.

A horizontal beam 117 is fulcrumed intermediate of its ends upon a post or standard 118 arranged adjacent to the rear end of 130

the tilting frame section 7 and is loosely connected at one of its ends to said frame section at the extreme outer side thereof. A weight 119 is suitably secured upon the other 5 end of this beam. In this manner, the tilting frame section is counterbalanced so that it may be readily moved or adjusted by the manipulation of the lever 103 with a minimum of manual labor. The vertical bars or 10 standards of the two carriage sections, at their inner opposed sides, are so placed relative to each other that they will not interfere by contact with a close arrangement of the carriage sections when a narrow stave 15 is to be cut.

From the foregoing description, taken in connection with the accompanying drawings, the construction, manner of operation and several advantages of my machine will 20 be clearly and fully understood. It is manifest, of course, that the angle of the cutting action of the saws must be changed for every different width of stave, but in every case the bevel on the side edges of the stave 25 will always be on a radial line intersecting the joint 11 between the countershaft sections and the hinge or pivotal connections between the two sections of the frame which represents the center of the hogshead or barrel. As the saws separate by the adjustment 30 of the tilting frame section, the top portions thereof will, of course, separate faster than the lower portions, and as each stave, regardless of its width, must pass the saws at the same point above their axial 35 centers and the medial portion of each stave at the same point relative to this axial center, it will be manifest that as the width of the stave is increased, the extent of its bulge 40 or longitudinal curvature is proportionately increased. Thus, it is not a matter of importance that narrow and wide staves are used in the same barrel or hogshead. The bulge in the individual stave will be precisely 45 proportionate to the total bulge in the hogshead, in accordance with the width of the stave, and the diameter of the hogshead at the ends thereof will accordingly be the same. By means of my improved jointing 50 machine, the staves may be quickly and accurately jointed, in precise accordance with the predetermined diameter of the hogshead or barrel. The machine being almost entirely 55 automatic in its action requires but little care or attention upon the part of the operator. As the several coöperating elements are of simple form and construction, it will also be appreciated that the machine 60 is not liable to get out of order. While I have shown and described the preferred construction and arrangement of the several parts, it is to be understood that the machine is susceptible of considerable modification therein and I, therefore, reserve 65 the privilege of adopting all such le-

gitimate changes as may be fairly embodied within the spirit and scope of the invention as claimed.

Having thus fully described my invention, what I desire to claim and secure by Letters Patent is:—

1. In a stave jointing machine, a stave carriage consisting of two sections coupled together for traveling movement as a unit, one of said carriage sections being angularly adjustable with respect to the other and the other carriage section having an operating movement in a single plane, manually operable means to variably space the adjustable carriage section from the opposed carriage section, means for actuating the traveling carriage, and means for securing a stave in position upon the carriage sections. 75

2. In a stave jointing machine, a stave carriage consisting of two sections coupled together for traveling movement as a unit, one of said sections having an operating movement in a single plane, means for angularly adjusting the other section to variably space the carriage sections from each other, means for securing a stave upon the carriage sections, and actuating means for the carriage coöperating with one of said sections. 80

3. In a stave jointing machine, a stave carriage consisting of two sections coupled together for traveling movement as a unit, one of said sections having an operating movement in a single plane, means for angularly adjusting the other section to variably space the carriage sections from each other, means for securing a stave upon the carriage sections, a longitudinally disposed rack fixed to one of the carriage sections, 100 and an actuating gear co-acting with said rack. 105

4. In a stave jointing machine, a stave carriage consisting of two sections coupled together for traveling movement as a unit, one of said sections having an operating movement in a single plane, means for angularly adjusting the other section to variably space the carriage sections from each other, means for securing a stave upon the carriage sections, a longitudinally disposed rack fixed to one of the carriage sections, an actuating gear co-acting with said rack, a latch element to co-act with the rack and hold the carriage against an operating movement, and means operatively connected to the latch element engaged and actuated by the stave when positioned upon the carriage to release the carriage for operation. 115

5. In a stave jointing machine, a fixed frame, a supplementary frame angularly adjustable with respect to the fixed frame, a rotary saw mounted upon each of said frames, operating means for each saw carried by the respective frames, carriage sec- 125 130

tions mounted upon the respective frames in opposed relation and means for angularly adjusting the supplementary frame to position the angular plane of rotation of the saw thereon with respect to the saw upon the other frame and simultaneously space the carriage section on the adjustable frame from the carriage section on the fixed frame.

5 6. In a stave jointing machine, a fixed frame, a supplementary frame pivotally connected to the fixed frame for angular movement with respect thereto, a rotary saw mounted upon each of said frames, carriage sections mounted upon the respective frames in opposed relation and means for angularly adjusting the supplementary frame with relation to the fixed frame to radially position the plane of rotation of the saw thereon with respect to the pivotal connection between said frames and simultaneously space the carriage section on the supplementary frame with respect to the carriage section on the fixed frame.

10 7. In a stave jointing machine, a fixed frame, a supplementary frame angularly movable with respect to the fixed frame, a rotary saw mounted upon each of the frames, countershaft sections journaled in said frames and operatively connected by a universal joint, means operatively connecting the countershaft sections to the respective saws, carriage sections mounted upon the respective frames in opposed relation and means for angularly adjusting the supplementary frame to radially position the plane of rotation of the saw thereon with respect to the joint connection between the countershaft sections and simultaneously space the carriage section on the supplementary frame from the carriage section on the fixed frame.

15 8. In a stave jointing machine, a fixed frame, a supplementary frame angularly movable with respect to the fixed frame, a rotary saw mounted upon each of the frames, countershaft sections journaled in said frames and operatively connected by a universal joint, means operatively connecting the countershaft sections to the respective saws, carriage sections mounted upon the respective frames in opposed relation, means for angularly adjusting the supplementary frame to radially position the plane of rotation of the saw thereon with respect to the joint connection between the countershaft sections and simultaneously space the carriage section on the supplementary frame from the carriage section on the fixed frame, and means for 20 counterbalancing the angularly adjustable supplementary frame.

25 9. In a stave jointing machine, a fixed frame, a supplementary frame pivotally connected to the fixed frame for angular

movement with respect thereto, a rotary saw mounted upon each of said frames, operating means for each saw mounted in the respective frames, carriage sections mounted upon the respective frames in opposed relation, means for angularly adjusting the supplementary frame to radially position the plane of rotation of the saw thereon with respect to the pivotal connection between said frames, and simultaneously space the carriage section on the supplementary frame from the carriage section on the fixed frame, and counterbalancing means for said adjustable frame.

30 10. In a stave jointing machine, a stave carriage, means for moving said carriage, means to co-act with the carriage and exert an initial impulse on the same in its operative movement, a latch member co-acting with a part on the carriage to hold the carriage in its starting position against the action of the last named means, and an element connected to said latch member and adapted to be engaged and actuated by the stave when the stave is arranged in position upon the carriage to operate said latch member, whereby the carriage is released.

35 11. In a stave jointing machine, a stave carriage, means for actuating said carriage, a latch member to co-act with a part on the carriage at the end of its movement in one direction and hold the carriage against reverse movement, a movable element, and means urging said element into co-acting relation with the carriage to impart an initial starting movement thereto when the latch device is actuated and the carriage released.

40 12. In a stave jointing machine, a stave carriage, means for actuating said carriage, a latch member co-acting with a part on the carriage to hold the carriage against movement in one direction, a movable element operatively connected to said latch member and adapted to be engaged and actuated by the stave when the stave is arranged in position upon the carriage to operate said latch member, whereby the carriage is released for movement, and spring-controlled means co-acting with the carriage to impart an initial starting movement to the same in its operating movement.

45 13. In a stave jointing machine, a stave carriage, means for actuating said carriage, a latch member co-acting with means on the carriage to hold the same against movement in one direction, a movable element operatively connected to said member and adapted to be engaged and actuated by the stave when the stave is arranged in position upon the carriage to move the latch member, whereby the carriage is released for movement, and a spring-controlled rod co-acting with the carriage to impart an

initial starting movement thereto when the latch device is actuated and the carriage released.

14. In a stave jointing machine, a fixed frame and a vertically tiltable supplementary frame, opposed carriage sections mounted to travel upon each of said frames, each of said sections having a forming head on its upper end, stave clamping means at the ends of each forming head, manually operable means to adjust the tiltable frame section and space the carriage sections in accordance with the predetermined width of the stave, and operating means mounted in the fixed frame and co-acting with the carriage section thereon.

15. In a stave jointing machine, a stave carriage having a forming head, means for holding a stave upon said forming head, a trip to actuate said holding means at the end of the travel of the carriage in one direction and release the stave, and means operating upon the stave to remove the same with respect to the carriage and discharge the stave from the machine.

16. In a stave jointing machine, a stave carriage having a forming head, means for holding a stave upon said forming head, a trip to actuate the holding means at the end of the travel of the carriage in one direction and release the stave, a stationary element to engage and lift the stave from the forming head, and means operating upon the stave to move the same longitudinally with respect to the carriage and discharge the jointed stave from the machine.

17. In a stave jointing machine, a stave carriage having a forming head, means for holding a stave upon said forming head, a trip to actuate the holding means at the end of the travel of the carriage in one direction and release the stave, rotary discharge means, and a stationary element to engage and lift the stave from the forming head and direct the same to the discharging means, whereby the stave is removed from the carriage and discharged from the machine.

18. In a stave jointing machine, a stave carriage having a forming head, means for holding a stave upon said forming head, a trip to actuate the holding means at the end of the travel of the carriage in one direction and release the stave, rotary discharge means, and a fixed, obliquely disposed rod to engage the under side of the stave and lift the same from the forming head and direct the stave to the discharging means, whereby it is removed from the carriage and discharged from the machine.

19. In a stave jointing machine, a stave carriage having a forming head, operating means for the carriage, clamping dogs at the opposite ends of the forming head to

engage and hold the stave thereon, a latch device to retain the carriage in its starting position, and means for actuating the latch device to release the carriage including an element engaged and actuated by the stave as it is placed in position upon the forming head.

20. In a stave jointing machine, a stave carriage having a forming head, operating means for the carriage, clamping dogs at the opposite ends of the forming head to engage and hold the stave thereon, a latch device to retain the carriage in its starting position, and means to actuate the latch device and release the carriage including a vertically movable rod normally projecting above the forming head and engaged and actuated by a stave when placed in position upon the forming head.

21. In a stave jointing machine, a stave carriage having a forming head, releasable means mounted on the head at its opposite ends to engage and retain the stave in position upon the head, a rack on the carriage, operating means co-acting with the rack, a latch element to operatively engage the rack and hold the carriage in its starting position, and means for actuating the latch element to release the rack including a part engaged and actuated by the stave as it is placed in position on the forming head.

22. In a stave jointing machine, a stave carriage having a forming head, means on the opposite ends of the forming head to engage and hold a stave in position thereon, a yieldable bumper limiting the movement of the carriage in each direction, a rack on the carriage, operating means co-acting with said rack, a latch element to engage the rack and hold the carriage against movement from its starting position under the action of the bumper, and means for operating the latch element to release the carriage including a vertically movable rod engaged and operated by the stave as it is placed in position on the forming head.

23. In a stave jointing machine, in combination with the rotary saws, a stave carriage, means for actuating said carriage, a pivoted member associated with each saw to receive the strip cut from one edge of the stave, an operating element connected to each of the pivoted members, and means to which said operating elements are connected, automatically actuated in the return movement of the carriage to simultaneously operate the pivoted members and discharge the strips from the machine.

24. In a stave jointing machine, in combination with the rotary saws, a stave carriage, means for actuating said carriage, a movable strip receiving member associated with each saw to receive the strip cut from one edge of the stave, a rock shaft, operative connections

between each of said members and the rock shaft, and means operatively connected to said shaft engaged and actuated in the return movement of the carriage to move the strip receiving members and discharge the strips from the machine.

25. In a stave jointing machine, in combination with the rotary saws, a stave carriage, means for actuating said carriage, a pivoted strip receiving member associated with each saw to receive the strip cut from one edge of the stave, an operating element connected to each of said pivoted members, and means operatively connected to said elements and actuated in the return movement of the carriage to actuate said pivoted members and discharge the strips from the machine.

26. In a stave jointing machine, in combination with the rotary saws, a stave carriage, means for actuating said carriage, a strip receiving member pivotally mounted for vertical swinging movement adjacent to each saw to receive the strip cut from one edge of the stave, a stationary, inclined deck

mounted adjacent to each of said members, a rock shaft, operative connections between each of the pivoted members and said rock shaft, and means connected to the rock shaft actuated by the carriage in its return movement to simultaneously elevate the pivoted members and discharge the strips therefrom upon said inclined decks. 30

27. In a stave jointing machine, in combination with the rotary saws, a stave carriage, means for actuating said carriage, a stationary, inclined deck arranged in spaced relation to each of the saws, movable strip receiving means mounted between the decks and the respective saws, and mechanism automatically actuated in the return movement of the carriage to operate the strip receiving means and discharge the strips upon said inclined decks. 35

40 In testimony whereof I hereunto affix my signature in the presence of two witnesses.
